BOTTLE CRATE

John D. Van Geem, 3931 Parkside Ave.,
Erie, Pa. 16508

Filed Feb. 23, 1971, Ser. No. 118,209

Term of patent 14 years

Int. Cl. D9—03

U.S. Cl. D9—177

FIG. 1

FIG. 2

FIG. 4

FIG. 3

FIG. 1 is an isometric view of a bottle crate showing my new design;

FIG. 2 is a side elevational view;

FIG. 3 is a fragmentary bottom plan view showing one-quarter of the bottle crate, the other three-quarters being identical but differently oriented; and

FIG. 4 is a fragmentary top plan view showing one-quarter of the bottle crate; the other three-quarters being identical but differently oriented.

I claim:

The ornamental design for a bottle crate, as shown and described.
